UNITED STATES PATENT OFFICE

SETH N. ELLIOTT, OF MARINE, ILLINOIS

WRENCH

Application filed August 25, 1930. Serial No. 477,699.

This invention relates to an improved wrench of the shiftable jaw type.

One object of the invention is to provide a device of this character employing a movable jaw which may be quickly and easily shifted to an adjusted position.

Another object of the invention is to provide a wrench employing a locking member which may be disposed out of engagement with the handle shank employed so that the movable jaw will be permitted to shift freely along the handle shank.

A further object of the invention is to provide a wrench wherein the movable jaw may be effectually locked in an adjusted position.

A still further object of the invention is to provide a wrench which will require a minimum amount of effort for its efficient operation.

Other and incidental objects of the invention not mentioned in the foregoing will appear during the course of the following description.

In the drawings:

Fig. 1 is a side elevation of the device,
Fig. 2 is a fragmentary vertical sectional view of the device,

Fig. 3 is a transverse sectional view on the line 3—3 of Fig. 2 looking in the direction indicated by the arrows, and

Fig. 4 is an enlarged fragmentary perspective view showing the locking member employed.

Referring now more particularly to the accompanying drawings, the numeral 1 indicates a preferably steel handle shank having inner and outer faces 2 and 3, and integrally formed on the upper end of said handle shank is an angularly disposed relatively fixed jaw 4 which is slightly enlarged in width with respect to said handle shank. Formed in the lower face of the fixed jaw 4 are serrations 5. Formed in the inner face 2 of the handle shank substantially medially of its ends are teeth 6, and disposed upon one of the side faces of the handle shank are graduations 6'. Screwed into the face 2 of said handle shank 1 at the base of the teeth 6 is a removable stop pin 7.

Slidable on the handle shank is a relative-

ly movable jaw 8 having serrations 9 formed in the upper face thereof to coact with the serrations 5 of the relatively fixed jaw. As best seen in Fig. 2 of the drawings, the jaw 8 is provided with a depending lug 10, and associated with the movable jaw and lug 10 is an angular spacing block 11 having teeth 11' formed thereon, said teeth being adapted to coact with the teeth 6 of the handle shank. The inner face of the block 11 is cut away, and mounted in said cut away portion is a curved preferably steel leaf spring 12 having its free end portion normally tensioned against the inner face 2 of the handle shank, the free end of said leaf spring being turned outwardly so that danger of accidental hooking of the spring 12, when the jaw 8 is shifted, will be prevented. Screwed into the shank 10 is a screw 13 for maintaining the spring in position.

Embracing the lug 10 of the movable jaw 8 and the block 11, and slidably connecting said jaw and block with the handle shank 1, is a yoke 14 which is cut away medially of its ends to define straps 15 and 16 slidably receiving the handle shank therethrough, the sides of the strap 16 being of slightly greater length than the sides of the strap 15. Connecting the yoke with the lug 8 and the block 11 are transversely extending rivets 17 and 18 formed integrally on the strap 16 is a spring seat 18 having a socket 19 and a straight flat inner face 20. The socket is substantially inverted frusto-conical in cross section. Disposed upon one of the sides of the yoke medially of the cut away portion and terminating at the edge of said cut away portion is an arrow 20' adapted to cooperate with the graduations 6' so that given settings of the movable jaw may be taken.

Slidably connected with the yoke 14 is a substantially U-shaped locking member which is provided with an elongated shank 21 gradually thickened toward its lower end and formed with an inclined face 22. Riveted or otherwise secured to the shank 21 is a wedging block 23 defining a shoulder 24, said block extending throughout substantially half the inner length of said locking member, and, as best seen in Fig. 4 of the

drawings, the wedging block is inclined to form a wedge face 25. Formed on one end of the shank is a thickened lug 26 having a rounded lower face and a flat upper face, while formed on the opposite end of the shank is a head 27 which is substantially rectangular. Screwed through the head 27 is a depending pin 28.

As shown in Figs. 2 and 3 of the drawings, the locking member is freely received between the sides of the strap 16 of the yoke 14 so that the straight outer face of the shank 21 of said member confronts the face 3 of the handle shank 1, while the lug 26 of said member projects beneath the lower end face of the spring seat 18. Associated with said locking member is a coil spring 29 having one end portion thereof engaging about the pin 28 and its opposite end portion engaging in the conical socket 19 of the spring seat 18, said spring normally urging the locking member upwardly.

Slidably embracing the yoke strap 16 is a substantially U-shaped hood 30 which is held in position on the locking member and head by removable pins 31 extending transversely through the lug 26 and the head 27 of said locking member, each of the pins being tapered toward corresponding ends for locking it in position. If desired, the pins may be straight and may be provided with heads at corresponding ends and nuts at opposite corresponding ends so that removal of the pins may be facilitated. Riveted or otherwise secured to the outer face of the bight portion of the hood 30 medially of its ends is a finger lug 32.

In use, the hood 30 is gripped and retracted for shifting the face 22 of the shank 21 of the locking member to a position opposite the flat inner face 20 of the spring seat 18, when the lower end of the hood may then be rocked outwardly to engage the shoulder 24 beneath the lower end face of said spring seat for holding the locking member and hood retracted. The shank 10 of the yoke may then be shifted away from the face 2 of the handle shank so that the teeth 11 are freed from the teeth 6. The movable jaw may then be shifted longitudinally of the handle shank. The relatively fixed jaw is first engaged with one side of the work to be moved, when the movable jaw 8 is shifted to engage the opposite side of said work. The hood 30 is then rocked toward the handle shank for freeing the shoulder 24 when the spring 29 will urge the locking member upwardly so that the wedge face 25 will coat with the face 20 of the spring seat 18 and cause the lower end portion of the shank of said member to bind between the spring seat and the face 3 of the handle shank 1 so that the yoke 14 will be rocked to engage the teeth 11 thereof with the teeth 6 of the shank. Thus the locking member will serve to effectually lock the mov-

able jaw when adjusted and, as will be seen, will effectually prevent accidental slipping of said jaw. Should the spring 29 become weakened so as to necessitate replacement thereof, it will be observed that the pin 28 may be removed and the spring withdrawn without displacing any of the other parts.

It is pointed out that, if the spacing block 11, the jaw 8, or the yoke 14 should become worn or mutilated, any of said parts may be withdrawn and replaced by removing the rivets 17.

Having thus described the invention, I claim:

1. A wrench including a handle shank having teeth and terminating at its upper end in a fixed jaw, a movable jaw associated with said fixed jaw and having teeth normally engaging the teeth of the handle shank, a yoke embracing the movable jaw and having straps surrounding the handle shank, one of said straps being extended to project rearwardly of said handle shank and being formed with a spring seat, a locking member associated with said latter mentioned strap and having an elongated shank slidably carried between the spring seat and the handle shank, said locking member having a head at its upper end and terminating at its lower end in a thickened lug, a pin screwed into the head, a spring having one end disposed in the socket and the other end surrounding said pin, said spring urging the locking member upwardly for retaining the teeth of the handle shank and the movable jaw in engagement, and a hood fitting about the head and the lug, said hood providing means for retracting the locking member and freeing the teeth of said movable jaw from the teeth of the handle shank and providing a housing for the spring, the locking member and the projecting portion of the strap.

2. A wrench including a handle shank having a fixed jaw, a movable jaw associated therewith, a yoke embracing said movable jaw and having straps surrounding the handle shank for slidably connecting said movable jaw with said handle shank, a locking member disposed between the outer portion of one strap and the adjacent face of the handle shank, means normally urging the locking member upwardly for rigidly connecting the fixed and movable jaws, and a hood connected to the locking member and outer portion of the last mentioned strap and having a finger lug, said hood and finger lug protecting the locking member and permitting ready manual retraction of said locking member for freeing the movable jaw with respect to the fixed jaw.

In testimony whereof I affix my signature.

SETH N. ELLIOTT. [L. S.]
